Inventor

Thomas Cost Marney

UNITED STATES PATENT OFFICE.

THOMAS COST MASNEY, OF BOSTON, MASSACHUSETTS.

TOBACCO PIPE.

Application filed September 26, 1925. Serial No. 58,790.

This invention relates to improvements in tobacco pipes and more particularly to attachments therefor.

An important object of the invention is to provide a pipe having a swinging cover mounted thereon adapted to permit the discharge of undesired matter therein.

A further object of the invention is the provision of a pipe of this character having a hinged cover plate mounted at the lower extremity of a suitable chamber formed in the pipe for the collection of tobacco and moisture.

A still further object of the invention is the provision of a pipe of this character having means for the collection and discharge of undesirable matter such as tobacco, ashes and moisture.

Other objects and advantages of this invention will be apparent during the course of the following description.

In the accompanying drawings forming a part of this application and in which like numerals are employed to designate like parts throughout the same:

Figure 1 is a longitudinal sectional view taken through the center of a pipe constructed in accordance with my invention,

Figure 2 is an enlarged sectional view illustrating the bore formed in the pipe for the collection of moisture and the like,

Figure 3 is a horizontal sectional view taken on the line 3—3 of Figure 2,

Figure 4 is a bottom plan view of the cover member,

Figure 5 is a side elevation of the same,

Figure 6 is a fragmentary longitudinal sectional view showing a slightly modified form,

Figure 7 is a cross section taken on line 7—7 of Figure 6,

Figure 8 is an enlarged fragmentary horizontal section of the modified form, and

Figure 9 is a horizontal section taken on line 9—9 of Figure 8.

In the drawings, wherein for the purpose of illustration is shown the preferred embodiments of my invention, the numeral 10 generally designates a common form of tobacco pipe comprising a bowl 11 and a stem 12 formed integral with the bowl and extending at substantially right angles to the lower portion thereof. A mouthpiece 13 is threadedly or otherwise mounted upon the outer extremity of the stem 12, this mouth-

piece being commonly constructed of rubber composition or similar material.

In common usage, pipes of this character

are provided with a longitudinal bore extending through the pipe stem and forming a passage connecting with the bowl, the mouthpiece being provided with a similar bore adapted to align with the bore formed in the stem. The smoke is usually drawn directly through this passage from the bowl, naturally carrying particles of tobacco and moisture which obviously collect therein, through this bore and into the mouth of the smoker. In my improved pipe illustrated in the drawings, I provide a transversely extending bore 14 formed in the stem and extending from the lower portion thereof to within a short distance of the upper portion, this bore forming a chamber or receptacle adapted to prevent the passage of tobacco and collect the moisture which may gather in the pipe. The mouthpiece 13 is provided with the usual longitudinal bore denoted by the numeral 15, while the stem 12 is provided with a pair of longitudinally extending bores 16 and 17. The bore 16 extends from the interior or bowl of the pipe to the chamber 14, while the bore 17 extends from the chamber to the extremity of the stem. The bores as clearly shown in the drawings are preferably out of alignment, the forward bore 17 connecting with the chamber at a slightly elevated position in relation to the bore 16 in order to prevent passage of matter directly through the stem. This arrangement of the bores in the stem enables the user to readily draw through the pipe, but causes the chamber formed in the stem to baffle the matter drawn directly from the bowl of the pipe, this matter collecting in the chamber. Saliva or other matter which may be deposited in the forward portion of the pipe stem and mouthpiece will naturally flow downwardly into the chamber and be retained therein.

Referring more particularly to the construction of the chamber or transverse bore formed in the stem, I consider it desirable to line the lower portion of the chamber with a tube 18, this tube being preferably of metallic construction and secured within the chamber by indentations 19 or in any similar manner. The lower edge of one side of the tube is provided with sections 20 adapted to form hinge members, the purpose of

100

95

105

110

which will be hereinafter explained. As it is desirable to enclose the lower portion of the chamber in a readily operable manner, I provide a cover plate 21, the lower face thereof being adapted to conform to the contour of the pipe stem. The upper side of the cover plate is of concave formation being provided about the periphery thereof with an extension edge or flange 22. A packing 5 ring 23 is mounted on the upper portion of the flange 22 and is preferably constructed of rubber or like yieldable material adapted to permit the cover to close the lower extremity of the chamber in an air-tight manner. As 10 it is desirable that the cover plate fit flush with the lower portion of the pipe stem, the lining tube 18 does not extend entirely to the extremity of the chamber, thus forming a recess in which the cover plate and packing 15 ring snugly fit. The edge of the cover plate is provided with a hinge member 24 adapted to align with the extension edges 20 formed on the lower portion of the tube 18, forming means by which the cover may be swung in 20 an open or closed position.

In order that the cover may normally swing in an open position, I provide a spring member 25, one extension thereof passing through the hinge sections and forming the 25 hinge pin and suitably fastened into the body of the stem as shown at 26. The other extremity of the spring member is bent upwardly and twisted to form a coil 27 and extends over the central portion of the cover 30 plate, thus having a tendency to force downwardly on the cover plate and normally retain same in an open position.

The cover plate is retained in the closed position by means of an arcuately bent rod 40 28, the upper extremity of this rod being adapted in certain positions to engage an arcuate groove 29 formed in the lower portion of the stem adjacent the chamber for this purpose. The other extremity of this 45 rod is threadedly or otherwise secured to a concave cap 29 adapted to fit within a suitably formed recess within the lower portion of the cover plate. The lower face of the cap 29 is provided with a plurality of rib 50 members 30 formed on the cap member and adapted to permit convenient rotation of the same.

In use, my improved pipe is designed to 55 obviate the disagreeable feature in pipe smoking, namely, the passage of particles of tobacco through the stem and the mixture of this tobacco with saliva, the resultant mass being drawn into the mouth of the smoker. As it is well known to those familiar 60 with the art, the assimilation of this matter is distasteful and also often sickening to the smoker and elimination thereof has been eagerly sought. I have accomplished this in a comparatively simple yet 65 readily conceivable manner, the formation

of the chamber 14 in the stem preventing the passage of this matter through the bore of the pipe and enabling same to be collected and discarded. The bores 16 and 17 formed in the pipe stem connecting with the chamber 14 out of alignment will prevent the smoker drawing particles of tobacco into the mouthpiece and mouth, these particles striking the walls of the chamber and collecting as residue at the bottom of the chamber. Moisture collecting in the forward portion of the stem and mouthpiece will naturally flow downwardly through the bores formed therein and also be deposited in the chamber, the bowl of the pipe usually being in a lower position than the mouthpiece. 70

After the pipe has been smoked for a substantial length of time, the chamber may be readily emptied and the matter collected therein emptied. This is accomplished by 75 merely forcing the finger against the cap 29, the ribs formed thereon permitting the same to be readily rotated and swing the upper portion of the rod 28 out of engagement with the arcuate groove formed in the stem, the spring 28 forcing the cover downwardly in an open position and permitting the undesirable matter collected in the chamber to be readily emptied therefrom. It is obvious 80 that this structure does not mar the appearance of the pipe nor make it necessary to provide cumbersome fixtures, the general structure of the pipe conforming very generally to the common form and being practically unnoticeable. 95

In Figures 6, 7, 8, and 9 of the official drawings, I have shown a slightly modified form of closure for the lower end of the vertical bore 14. In this form the tube 18 terminates slightly above the lower face of the stem 12, so as to provide a shoulder 35. The shoulder 35 is engaged by an annular enlarged portion 36 formed on the disk shaped closure member 37, while the periphery of the disk shaped closure member 37 above the annular portion 36 engages the interior of the tube 18. On the upper face of the closure disk 37 is attached a plate 38 which has extending centrally therethrough one extremity of a wire 39, 100 said extremity having a head 40 formed thereon which engages under the plate 38 so as to pivotally connect the closure member 37 to the wire 39. The wire 39 after being attached to the closure member extends 105 towards the tube 18 slightly above the plate 38 and is coiled, as at 40', for providing means for swinging the closure member outwardly when said closure member is released. After forming the coil 40' the wire extends 110 upwardly, as at 41, engaging the interior of the tube 18 and bore 14 and is then looped or turned back upon itself to provide a pair of parallel spaced strands of wire. The extremity after forming the loop is bent 115 120 125 130

over the strand of wire 39 adjacent the coil 40', so as to provide an elongated loop 42. Extending through the loop 42 is a small nail 43, or the like, which also extends 5 through the tube 18 and into the stem 12, said nail having an enlarged head 44 provided thereon for slidably retaining the elongated loop 42 against the interior of the tube 18 and interior of the bore 14.

19 Arranged to project slightly inwardly into the bore 14 at the lower portion thereof below the sleeve 18 is a pair of pins 45, which are adapted to be received in L-shaped grooves 46 formed in the periphery of the 15 annular portion 36 of the closure member 37 for holding the closure disk 37 in a closed position.

In this form of my invention, it can be seen that when it is desired to open the 20 lower end of the bore 14, the closure disk 37 is slightly turned by the operator engaging the same with the thumb, said turning movement permitting the L-shaped grooves 46 to be disengaged from the pins 45, which will 25 cause the closure member 37 to be swung outwardly by the coil 40' formed on the wire 39. It can be seen that when the coil 40' swings the closure member 37 that said closure member and wire 39 will be moved 30 downwardly, the loop 42 sliding upon the pin 43, thus swinging the closure member to a position which will permit ready access to the bore 14.

It is to be understood that the forms of 35 my invention herewith shown and described are to be taken as the preferred examples of the same, and that various changes as to the shape, size and arrangement of parts may be resorted to without departing from the spirit of the invention, or the scope of 40 the subjoined claims.

Having thus described my invention, I claim:

1. A device of the character described comprising a tubular container formed in 45 a pipe or the like, a cover plate hingedly mounted on the lower extremity of the said container, means for normally forcing the cover plate in an open position, a rod member adapted to retain the cover plate in a closed 50 position, and means for readily operating the said rod member.

2. A tobacco pipe having a bore formed in the stem thereof, a tubular sleeve mounted in the said bore, a cover plate hingedly 55 mounted on the lower extremity of the said sleeve, a packing ring mounted on the said cover plate, a spring member adapted to normally force the cover plate in an open position, a locking rod rotatably mounted 60 through the cover plate adapted to lock the cover in the closed position, and means for readily operating the said locking rod.

3. A tobacco pipe having a transversely extending bore formed in the stem thereof, longitudinal bores formed in the said stem and connecting with the said transverse bore, a sleeve mounted in the lower portion of the said transverse bore, a cover plate hingedly 65 mounted on the lower extremity of the said sleeve, a packing ring positioned about the lower edge of the cover plate, a spring member secured to the said hinge adapted to normally retain the cover plate in an open position, a locking lever rotatably mounted in the 70 said cover plate adapted to engage a suitable recess formed in the said stem, and a cap secured to the lower portion of the said locking lever for readily rotating the same.

In testimony whereof, I have affixed my 75 signature.

THOS. COST MASNEY. [L. s.]
